(57) **CLAIM**

The ornamental design for a lawn aerator, as shown and described.

DESCRIPTION

FIG. 1 is a top perspective view of a lawn aerator showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 shown in FIG. 2; and,

FIG. 10 is a partial enlarged view of portion 10 shown in FIG. 3.

The dot-dash broken lines in the drawings depict the boundaries of the partial enlarged views that form no part of the claimed design.

1 Claim, 10 Drawing Sheets
